UNITED STATES PATENT OFFICE.

LUCIEN E. ROSS, OF MEMPHIS, TENNESSEE.

AUTOMATICALLY-DISAPPEARING STORM CURTAIN.

Application filed March 16, 1926. Serial No. 95,167.

This invention relates to storm curtains primarily adapted for use on automobiles.

The main object is to provide a novel construction wherein a curtain or curtains will tend to automatically fold in accordion fashion to a position out of use.

Another object is to provide a novel means whereby the curtains may be fastened in their operative or storm position by novel means and against the folding influence.

Still another object is to provide a construction which may be readily applied to existing types of curtains, thus forming an attachment, whereby the same will automatically tend to fold, in accordion fashion and assume a position out of sight.

It is still further aimed to provide a novel construction of spring controlled rods, links, and the like to accomplish the end stated and which will be set forth in detail hereinafter in accompanying drawings illustrating one operative embodiment.

In the drawings:

Figure 1 is a view in substantially central longitudinal section through an automobile, the latter being shown fragmentarily and showing my improvement in operative position;

Figure 2 is an enlarged side elevation of one of the curtains looking from the interior of the automobile, and in connection with fragments of the latter;

Figure 3 is a sectional view taken on line 3-3 of Figure 2;

Figure 4 is a detail elevation of one side of the folding means for a curtain;

Figure 5 is an end view of said folding means of Figure 4;

Figure 6 is a view taken on the line 6-6 of Figure 4; and

Figure 7 is a sectional view taken on the line 7-7 of Figure 4.

By way of example, an automobile has been shown conventionally at A. B designates the top cover or canopy thereof supported for instance by upright bows C at the front and an inclined arc-shaped bow D at the rear, as well as intermediate bows as at E. The front and rear seats respectively are designated F and G. Any suitable number of curtains 10, for instance three, as shown, may be used and be adapted for individual operation. As the vehicle shown is a touring car, the number is preferably

three. The body of each curtain may be of any desired material but usually is made of rubberized fabric or other flexible material. Any suitable number of glass, celluloid, or other lights as at 11 are provided for each curtain.

The arrangement and illustration of the curtains in Figure 1 applying to one side only, it might be mentioned that the same is duplicated on the other side of the vehicle.

Suitably fastened to the bows C and D, for instance, at each side of the vehicle, is a longitudinal baton 12, preferably of wood and covered with cloth. The curtains 10 as at 13 are nailed, stapled or otherwise secured at their upper edges to the baton 12. Each curtain is fastened in its operative position as shown in Figures 1 and 2 in any suitable manner as by means of fastenings as at 15 separably engaging studs 15^a on the vehicle body or its doors.

Arranged longitudinally of the curtains and rigidly attached thereto as by suitable keepers 27^a secured to the curtains, are rods 28 having collars 29 rigidly and removably fastened thereto as by removable pins 30. Suitable links 31 are employed which are arranged transversely of the curtains, having eyelets 32 at each end and being of a length for pivotal disposition on the two adjacent rods 28 as shown, and being secured against detachment as by cotter keys 33 passing through the rods 28. It will be seen that the uppermost rods or links 31 are outermost and that such links are disposed inwardly serially in a downward direction. Links 31 are fastened in place by keepers 35 secured to the curtain. By this structure it will be understood that each curtain is formed in a series of panels defined by the rods 28 and links 31 that are foldable on one another by the instrumentalities hereinafter described in detail.

Coil springs 38 surround all of the rods 28 except the lowermost row, adjacent their outer ends, and have terminals 32^b and 32^a removably engaging openings or sockets 34 and 34^a, respectively, provided in the collars 29 and adjacent links 31, respectively. Springs 38 are under tension and, when the curtains are unfastened or are free except with respect to the baton 12, will automatically fold to the dotted line position shown

in Figure 3, due to the tension of the springs 38. The curtains thus disappear or move to the dotted line or concealed position of Figure 3 under the top 2 and adjacent the 5 sides thereof.

The folding is in accordion fashion and in the folded position, the fasteners 15 may engage studs 40, carried for instance by a baton 41, preferably covered with cloth and 10 secured for instance to the bows D and E supporting the top B.

Attention is called to the fact that the 15 inclined row of the links 31 as used with each back curtain does not interfere with the folding due to the fact that there is sufficient clearance at the joints of the links 31 with the rods 28. Also, suitable separable fastening means may be provided as at 20 44 and 45 between the front and rear curtain and the bows C and D.

In use, the curtains are normally in the folded or disappeared position suggested by the dotted lines in Figure 3, and securely held in that position not only by the springs 25 38 but also by the engagement of fastenings 15 with the studs 40. In order to lower the curtains, the fastenings 15 are disengaged from the studs 40 and the curtains moved to an upright or full line or unfolded 30 position as shown in Figures 1, 2, and 3, being secured in such positions by the engagement of the fasteners 15 with suitable studs and also by the fastenings at 44 and 45. In order to fold or raise the curtains, 35 it is merely necessary to detach the fastenings 15 from said studs and the fastenings 44 and 45, whereupon the springs 38, due to their tension, will automatically fold the curtains into the dotted line position of 40 Figure 3, after which the fastenings 15 are preferably engaged with the studs 40.

Various changes may be resorted to provided they fall within the spirit and scope of the invention.

45 What is claimed is:—

1. In combination with a flexible curtain, rods longitudinally secured thereto in parallel relation, links secured transversely to the curtain and pivotally engaging said 50 rods, said rods and links dividing the curtain into a plurality of panels, and spring means engaging said rods and links and

urging folding movement of said panels in substantially accordion fashion.

2. In combination with a flexible curtain, 55 rods longitudinally secured thereto in parallel relation, links secured transversely to the curtain and connected to the rods at their ends, said rods and links dividing the curtain into a plurality of panels, oppositely disposed links having one of their ends secured to one of the rods and their other ends pivotally engaging an adjacent rod, and spring means engaging said rods and the pivoted ends of said links, said spring 60 means on adjacent rods being oppositely tensioned to fold the panels on one another in substantially accordion fashion.

3. A curtain of the class described having longitudinal rods secured thereto, collars on said rods, means removably and rigidly securing said collars to the rods, links secured to the curtain and pivotally connected to the rods, said rods and links dividing the curtain into a plurality of panels, tensioned springs surrounding the rods intermediate the collars and the links, and said springs having terminals removably disposed in said collars and said links, said 65 springs urging automatic folding 70 movement of the panels in substantially accordion fashion.

4. A curtain of the class described having longitudinal rods thereon, collars on said rods, means removably and rigidly securing said collars to the rods, links on the curtain pivotally connected to the rods, tensioned springs surrounding the rods intermediate the collars and the links and said 75 springs having terminals removably disposed in said collars and said links, said springs urging automatic folding 80 movement of the curtain, keepers on said curtain for said rods and links, a baton to which the curtain is fastened, a second baton having 85 studs, means on the curtain adjacent the lower edge thereof to secure the same in operative position against the tension of 90 said springs, and the last mentioned means being engageable with said studs in the 95 folded position of the curtain.

In testimony whereof I affix my signature.

LUCIEN E. ROSS.
